WELL SCREEN STRUCTURE

William J. Banchback, Aurora, Ind.

Application July 14, 1952, Serial No. 298,810

6 Claims. (Cl. 166—231)

1

The present invention relates to well screens and comparable devices such as drive well points and has for an object the provision of devices of this kind that are exceptionally strong and efficient, and of a method whereby they can be made at a reasonable cost.

Another object of the invention is to provide a structure of this kind including longitudinal bars and a helical winding of keystone wire secured thereto in a manner which provides for mutual mechanical interlock and mutual reinforcement of the parts so that accuracy of flow slot size may be maintained under adverse handling conditions.

A further object of the invention is to provide a method of forming devices of this kind wherein the base of the keystone wire is bent laterally in slots in the bars thereby strengthening the winding and simultaneously effecting the interlocking thereof with the bars.

A still further object of the invention is to provide a device of this kind with a maximum length of accurate and continuous flow slot to afford efficiency in operation.

These and other objects are provided by the means and method described herein and exemplified in the accompanying drawings in which:

Fig. 1 is a side elevational view of a well screen embodying the invention, part being broken away.

Fig. 2 is a cross sectional view taken on line 2—2 of Fig. 1.

Fig. 3 is a cross sectional view taken on line 3—3 of Fig. 1 and illustrating the successive steps in the construction of the device.

In the manufacture of well screens and the like various arrangements have been used or suggested in attempts to secure, at reasonable cost, a structure that is strong and efficient but all of these have left much to be desired. The practice of welding the winding and bars together and the practice of caulking the metal of the bars and/or winding have both presented difficulties of one sort of another.

According to the means and method of the present invention I employ a keystone type winding wire 5 of a special shape in which the base or web 6 is much higher than the keystone head 7 and secure the turns of such wire 5 in specially formed angularly turned slots 8 formed in the bars 9 of the screen structure as exemplified herein and indicated generally at 10. The bars 9 are wide and may be relatively thin and these are initially arranged to be held edgewise in radial relation to the center axis of the well

2

screen to outline a cylinder about which the keystone head 7 of the wire is arranged in accurately spaced turns to provide a continuous and uninterrupted selfcleaning flow slot 11.

5 The simple, strong and mutually reenforcing structural connection which eliminates previous difficulties in well screen construction consists in forming in each bar 9, where the winding intersects it, a slot 8 which extends perpendicular to the outer edge face 12 of the bar and then has an angularly turned extension 13. Into each angle slot 8—13 the entire base or web 6 of the keystone wire is fitted, leaving the head or keystone portion of the wire to form a helix of spaced turns extending outside the outer edge faces 12 of the bars so that the inwardly divergent slot 11 is continuous and uninterrupted.

As can be best understood from an inspection of Figs. 1 and 3 any desired number of bars 9, sufficient to support the required winding to provide a predetermined flow space 11, may be employed. Said bars 9 are arranged edgewise radially of a common center axis and in longitudinal parallelism to form the outline of a cylinder.

20 Any suitable mandrel (not shown) may be used for holding the bars in position during construction of the well screen, and an end coupling member 14 is applied to the bars 9 by threaded and/or brazed connection at 15. The bars 9 are 25 by preference initially unslotted and the bar slots 8—13 are formed successively in adjacent bars along the path of a helix while the base of the winding wire is entered and then turned laterally to conform to the cross section of the slot in the bar.

30 As will be best understood from an inspection of Fig. 3, if the size of the well screen and the size of its flow slot be such that a relatively thicker keystone wire is indicated, then it is desirable that a longitudinal groove 16 be cut along the side face of the wire base 6 to assure bending of the base 6 along the line of said groove as the base is forced into the angle slot in the bar.

35 The wire 5 has its base guidedly fed into the vertical portion 8 of the slot whereupon any suitable pressure means, e. g. a roller indicated in dashed lines at 17 forces the leading edge of the base 6 into the angularly related portion 13 of the slot until the slot 8—13 is completely 40 filled with the base 6 and the keystone head 7 of the wire extends from the outer edge of the bar. The act of laterally bending the wire to conformity with the cross section of the slot 8—13 effects a work hardening of the wire which 45 cooperates to further strengthen the helical

winding while the laterally turned longitudinal bend is progressively formed in the wire.

A strong positive interlocking binding of the wire at each slot in each of the bars is thus effected. The overall structure of a well screen (or a drive well point) thus formed is strong and rigid and it resists distortion under any and all kinds of strains and stresses that may be imposed on it. The metal of the bars is not weakened by caulking of its metal as in some known forms of well screens. Instead the winding and the bars mutually reinforce each other. The overall weight of materials may be appreciably less than in known screens intended and designed for identical duty.

When the strainer structure is of small diameter and the flow slot 11 is very narrow, a key-stone wire therein indicated may have its web thin enough to be bent without the use of a groove such as 16.

The method of speedily making well screens according to the invention consists essentially in supporting the bars 9 to outline a cylinder, progressively cutting the angle slots 8-13 along the path of a helix of desired lead, guidedly entering the base of the keystone wire to the full depth of the vertical slot portion 8 in the bar and finally exerting force on the top of the keystone head of the wire to cause the base of the wire to bend laterally into conformity and mutually interlocking relation with the angle slot 8-13. The angle slot 8-12 may be formed in various ways by means forming no part of the present invention.

What is claimed is:

1. A well screen device comprising a plurality of thin wide support bars arranged radially edge-wise about a common center axis, said bars having angle slots in spaced relation and disposed along a helical path about the plurality of bars, the slots being parallel sided and each slot entering perpendicularly into the edge of the bar for a distance and then turning obliquely toward one end of the bar, and a keystone wire having a parallel sided base entered fully in and laterally bent along its length into conforming relation to each slot and disposing the keystone head thereof outwardly of the outer edges of said bars.

2. In a device of the class described the combination of a plurality of thin wide bars arranged edgewise radially about a common center axis, the bars having slots extending from the outer edges thereof perpendicularly for a distance and then angularly inclined toward a common end of the bars, and a keystone wire including a base fitting snugly into the perpendicular and angularly inclined portions of the slot to form a mechanical interlock of the wire base in each of said slots and to provide a longitudinal reenforcing bend in the wire.

3. In a well screen the combination of parallel bars arranged to outline a cylinder and successively slotted to define a helical path passing through the outer portions of the bars, the slots each extending radially inwardly from the outermost portions of the bars and thence inclined toward a common end of said bars to present an angular cross section shape, and a keystone wire having a keystone shaped head located beyond the open end of the slot and a base having a longitudinal extending reinforcing bend con-

forming to the cross section of said base to the cross section of each groove and forming an interlocking permanent connection of the base of the wire within each slot in each bar.

5   4. The method of making a well screen which
comprises the steps of disposing a plurality of
bars in parallelism in the outline of a cylinder,
progressively cutting angle slots in successive
bars to define a helical path in the plurality of
10   bars, said slots extending from the outer edge of
the bar perpendicularly for a distance and then
inclined angularly toward a common end of the
bar, entering the base of a keystone wire into the
open top of each slot on completion of the cut-
15   ting thereof and forthwith subjecting the head
of the keystone wire to pressure and causing the
base of the wire to bend laterally into completely
filling and interlocking relation with the sides of
the angle slot.

20 5. The method of making well screens and the
like which comprises the steps of forming a shal-
low longitudinal groove in one side wall of the
base of a keystone wire, arranging a plurality of
bars in the outline of a cylinder, progressively
25 forming angle slots in successive bars along a
helical path, said angle slots being parallel sided
and entering perpendicularly from the outer edge
of the bar for a distance and then inclined angu-
larly toward an end of the bar, feeding the base
30 of the wire into the open tops of said slots suc-
cessively and forthwith forcing the base of the
wire into the successive slots for forming a work
hardened reenforcing bend extending longitudi-
nally of the wire from said groove to the end of
35 the base as said end of the base enters and fills
the angle slots whereby an interlocking mechan-
ical connection is completed between the wire base
and the bars at each slot in said bars.

6. The method of making well screens and the
like comprising the steps of longitudinally groov-
ing a keystone wire along one face of the base
thereof, supporting a plurality of bars radially
edgewise in the form of the outline of a cylinder,
progressively forming parallel sided angle slots
in successive bars along a helical path about said
plurality of bars, the angle slots each including
a top portion extending from the outer edge of
the bar perpendicular thereto for a distance equal
to substantially the distance between the key-
stone head of the wire and the groove in the base
thereof, said slot extending angularly from said
top portion toward the end of the bar, the total
cross sectional area of the wire base being sub-
stantially equal to the cross sectional area of the
slot, and successively forcing the base of the key-
stone wire into the successive slots while winding
the wire about the bars for laterally bending the
base of the wire to conform the shape thereof to
the shape of the slot, said bending operation at
least partially closing the groove in the side of
the wire base.
